Specification of Letters Patent.

Patented May 11, 1920.

Application filed March 28, 1919. Serial No. 285,828.

To all whom it may concern:

Be it known that I, ELWOOD GRISSINGER, a citizen of the United States, and resident of Buffalo, in the county of Erie and State of New York, have invented certain new and useful Improvements in Phonograph and Analogous Apparatus, of which the following is a specification.

My present invention is shown as embodied in a phonographic sound box which is primarily adapted for mechanically reproducing sound from a record, but may be employed for the reverse process of recording sound upon a wax or other impressionable surface. The general purposes and objects of my present invention are similar to those explained in my prior applications Ser. Nos. 236,735, 239,512 and 239,513; and the novel features of my present device may be employed in connection with the recording apparatus and methods of my application Ser. No. 236,735.

One important object of my present invention is to insure faithful transmission through a lever or other similar machine element, of physical movements corresponding to speech vibrations or other vibrations having similar frequencies or similar complexities. Certain features of my invention which contribute to this object are capable of useful employment not only in phonographs but also in other instruments wherein faithful execution or transmission of complex or high frequency movements is necessary or desirable.

In phonograph apparatus, the sounds are represented solely by physical to and fro movements of the diaphragm, lever and stylus, and the wide variations in loudness, pitch and quality are represented solely by variations in the frequencies, speeds and distances or amplitudes of these physical movements. In recording, the lever is actuated by the diaphragm, and the stylus at the other end of the lever, records the resulting movements as undulations in a groove which the stylus cuts in the moving record. These undulations may be cut either in the side walls of the groove as in machines of the Victor talking machine type or in the bottom of the groove as in machines of the Edison type. In reproducing the process

is reversed, the undulations in the record actuating the stylus, lever and diaphragm to reproduce in the air, the sounds corresponding to those originally recorded.

All of the physical factors concerned are of extraordinarily small magnitude and the minutest physical or mechanical imperfection shows up as an enormously magnified disturbance in the sound produced by the phonograph diaphragm. Hence, one of the primary objects of my present invention is to secure in a single device the required high degree of mechanical strength and precision of operation, combined with extremely sensitive response to all of the variations characteristic of complex or high frequency sound waves. In my present device, the lever is substantially rigid. The pivoting of the lever is substantially noiseless and free from any trace of rubbing, jumping or other relative movement of pivotal contact surfaces. The oscillatory movements of the lever are confined to a single plane and all twisting, skewing or other movements or vibrations of the lever are prevented, except only the desired to and fro movements in a direction perpendicular to the diaphragm.

The noiseless, rigid pivoting and the noiseless springs and the levers free from vibratory movement in directions not perpendicular to the diaphragm, are especially important in devices of the Victor talking machine type in which the pivot lies in a plane perpendicular to the record, and the minute, unavoidable inequalities in the bottom of the groove tend to vibrate the stylus vertically in directions not perpendicular to the diaphragm, thus causing disturbing noises at the same time that the sound record undulations in the sides of the grooves are operating to produce the desired sounds by the desired vibration perpendicular to the diaphragm.

The special features of my construction whereby I secure the noiseless, frictionless, rigid pivoting in combination with any desired degree of sensitiveness and ease of the pivotal movement in the desired plane, also make it possible to secure certain other essentials of faithful phonographic reproduction which have not been appreciated.

2
or achieved heretofore, either practically or theoretically.

5 The additional requisite is that the lever should execute and transmit the physical movements corresponding to each and all of the fundamental and component frequencies of speech and music, with equal efficiency, that is, without disproportionately amplifying any of said frequencies and without disproportionately diminishing any 10 of them.

15 The disproportionate amplifying of certain frequencies either fundamental or components, commonly results from mechanical resonance or "natural vibration" of parts 20 of the vibratory system or of the system as a whole.

25 The disproportionate diminishing of certain of the frequencies commonly results from excessive pressure and friction of the stylus on the record—such pressure diminishes the ease and freedom of movement which is necessary for faithful reproduction of the higher-frequency, small-amplitude components of the sound and it operates 30 to damp out such high frequencies more than the lower ones. It is commonly employed however in an attempt to control and damp out the disproportionate amplifying due to mechanical resonance.

35 Mechanical resonance is therefore the direct cause of disproportionate amplifying of certain frequencies and the reason or indirect cause for the pressure and damping which disproportionately diminishes the 40 higher frequencies. One object of my invention is to do away with the mechanical resonance and so do away with the necessity for damping.

45 My invention recognizes, however, that in apparatus of this kind, the natural elastic qualities which cause mechanical resonance are unavoidable; that the resonance effects may come from natural vibrations of certain 50 elements of the vibratory system as well as from natural vibrations of the system as a whole; and, finally, that the effects of these natural frequency vibrations can be avoided and completely eliminated from the functioning of the device, by making the natural frequency of the elastic elements too high for audibility in the phonograph and the natural frequency of the system as a 55 whole too low to be noticeable in the phonograph. I believe these two conditions or qualities have never before been embodied in a single instrument. This is because a low enough natural frequency for the lever requires that the inertia factor be very 60 great or the elasticity factor very small, yet the inertia cannot be great because the lever must be extremely light in order to properly perform its phonographic functions and the spring elements must have extremely high 65 resilience in order that their individual nat-

ural frequencies may be higher than any of the frequencies that are audible in the phonograph.

With the above difficulties and purposes in view, I employ a light but rigid construction whereby the lever moves as a unit, substantially without independent or "natural" vibrations within the range of phonographic frequencies. Furthermore, I employ resilience or spring members under extreme high tension, such as will prevent any disturbing movement or skewing of the lever or of its pivotal axis, and such as will raise the natural vibrations of said spring elements to a frequency higher than any of the 70 frequencies within the range mentioned. At the same time, the arrangement of these spring members is such that their enormous tensions are substantially balanced on the lever and there remains only a small resultant resilience available for elastic restoration of the lever. Hence the natural frequency of the whole vibratory system may be kept as low as required even though the lever be very light and the individual tensions of the separate springs very powerful. 75

Having thus eliminated mechanical resonance without rendering the vibratory system either stiff or sluggish, I am able to use a light sound box with minimum pressure and friction of the stylus on the record. Frictional damping being minimized, the remaining damping factors are mainly those due to inertia of the lever and internal molecular friction in the material of the vibratory parts. These are approximately 80 constant and their damping effects are not objectionably greater for the high frequencies than for the low frequencies. Hence, this kind of damping does not operate to 85 distort the sounds objectionably.

In the present embodiment of my invention, the resilient or spring elements comprise one or more highly tensioned wires, clamped on opposite sides of and preferably 90 extending through the lever, in combination with a pivotal bearing adjustable in a direction at right angles to the wires. Highly tensioned wires for similar purposes are used in the devices of my prior applications 95 above referred to but in those devices, the wires were spaced apart and symmetrically positioned with respect to the pivotal axis, that is to say, they converge and diverge 100 equally and oppositely with respect to said axis so that their tension stresses are balanced against each other and against the thrust of the stationary bearing. With such arrangement, it is not easy to keep the divergent wire tensions symmetrical with respect to the thrust of the bearing during 105 adjustment of the latter, because in practice the wires sometimes stretch and yield unequally and sometimes the thrust of the bearing does not take effect exactly midway 110

between the wires and hence the thrust acts to apply greater strain on one wire than on the other. My present invention contemplates an improved arrangement whereby 5 the same high tension is available to press the lever into perfect non-slip contact with the pivot bearing, and said bearing is adjustable to stretch the wire to a very high tension but instead of having two wires 10 with balanced tensions, only one wire need be used and if more wires are used, they are deflected and stressed in the same direction and in the same plane, said plane being the plane of pivotal contact of the bearing 15 against the lever which is also the plane in which said bearing is adjusted to stretch the wires to the required high tension.

The stability characteristic, that is the maintenance of a normal plane of rest for 20 the lever from which pivotal movement is elastically resisted and toward which it tends to return, is obtained by employing a convex curved surface for the stationary bearing, as for instance, a cylindrical surface 25 or a pair of aligned spherical balls. One highly tensioned wire disposed in a plane passing through the line of pivotal contact and through the axis of the spheres or cylinder, will give the desired self-restoring 30 or stability characteristic because the relatively enormous tension of the wire pressing the lever squarely down on the curved bearing surface will prevent slip and will compel non-slip rocking of the 35 lever upon the sphere, throughout a very considerable arc of pivotal movement—an arc much greater than required for phonographic purposes.

In this connection, particular attention 40 is called to the fact that such stable equilibrium will not result where a curved bearing surface is used on the lever in combination with a plane rocking surface on the sound box, except in certain special cases, 45 as, for instance, where the points of engagement of the wire with the lever are on a line located between circumference of the curved bearing surface and its axis of curvature.

50 In certain cases, cross-sectional and transverse elasticity or stiffness of the material of the wire may be a factor in producing self-restoring resilience of the lever, but in the preferred arrangements, the arc of 55 lateral movement of the wire is very small, so that the stiffness of the material of the wire is not likely to be an important resilience factor, particularly where the wires are not very thick and short.

60 By my preferred arrangement wherein the ball or cylinder surfaces are on the box, and wherein the wires and the line of contact and the center or axis of curvature of the curved bearing surface all lie approximately in the same plane, the self restoring

resilience of the lever movements will increase with increasing tension of the wire, and for equal tensions will increase with increase of the angle between the unclamped portions of the wire and the pivotal axis. 70 Hence, forcing the adjustable bearing against the lever increases the certainty of perfect, non-slip pivoting not only by increasing the amount of the tension of the wire but also by increasing its effective 75 angle of pull toward the pivotal axis.

By using two or more wires disposed in substantially the same plane and preferably parallel but not touching each other, the total tension may be multiplied without exceeding the tensile strength of the wires. 80 Using more wires is usually preferable to increasing the diameter of a single wire. This is especially true where the preferred material, piano steel wire, is employed, because in the larger sizes, the wire is apt to be too stiff and stubborn for smooth, abrupt bending without breaking, at the points of sharp deflection adjacent the clamps and adjacent the points of engagement with the lever. Independently of the above factors, the self-restoring power may be decreased within wide limits by decreasing the diameter of the bearing balls.

With the above variables at command, I 95 can get any required degree of sensitiveness and small pivotal resilience for the lever, substantially independently of the high tension of the wires. Moreover, the adjustment of the bearing to tension the wires 100 does not change the plane of bearing thrust and wire tension. Hence, I have no difficulty in getting a wire tension sufficient for perfect non-slip pivoting and for a natural frequency of the unclamped portions of the 105 wire too high to be noticeable, while at the same time keeping the resilient self-restoring effect of the wire tension on the lever so small that the natural frequency of the vibratory system as a whole, is too low to 110 produce objectionable effects.

The various features of my invention may be more fully understood from the following description in connection with the accompanying drawings of a desirable embodiment of my present invention.

In the drawings:

Figure 1 is an elevation or face view of a phonographic reproducer embodying one form of my invention;

Fig. 2 is an end view of Fig. 1 from below;

Fig. 3 is a section on the line 3—3, Fig. 1;

Figs. 4 and 5 are sections on the line 4—4 showing an initial position and one of the 125 adjusted positions of the parts;

Figs. 6, 7 and 8 are respectively face, end and sectional views corresponding to Figs. 1, 2 and 3 but showing a modified arrangement of the pivotal mounting;

Figs. 9 and 10 are respectively longitudinal section and face views of a form of lever arranged for use with a single wire.

The device in which the invention is embodied comprises the recessed frame 1 and cover 2 inclosing a diaphragm 3 clamped between rubber cushions 4—4 and provided with an annular coupling member 5 having a projection 6 adapted for locking engagement with the tone arm of the phonograph. The coupling member is secured by screws 7 against the cushion 8. The frame 1 is provided with an integral projection 9 forming a bracket support for the pivotal mounting of the stylus lever 10. The stylus lever is shown as rigidly connected to the diaphragm by the bolt 11 passing through perforations in diaphragm and lever, secured to the diaphragm by clamping nuts 13 and to the lever by clamping nuts 14.

The above parts may be of any known or desired construction but in any event the sound box and lever should be strong and rigid and are preferably made of aluminum since employment of my present invention makes it unnecessary to have a heavy sound box pressing the stylus heavily in contact with the record.

As shown in Figs. 3, 4 and 5, the stylus lever is provided with a steel block or insert 15 affording hard, preferably polished, bearing surfaces 16, 16, for rocking engagement with the ball bearings 17, 17, which are preferably of very hard polished steel. The bracket 9 is also provided with steel inserts 18, 18, having screw threaded projections 19, 19, formed with one or more sets of aligned passages 20, 20, and 21, 21, through which one or more tension wires 22, 23 are threaded and in which they are clamped between steel washers 24, threaded nut 25, washer 26 and nut 27.

I have discovered that the wire passages through steel insert 15 on the lever as well as the clamping washers and nuts on studs 19 should be of steel and preferably of very hard tool steel, for in practical use of the device, I have found that the constant vibration of the lever will cause the wires, when deflected and highly tensioned as shown in Fig. 5, to rapidly cut the metal even though it be as hard as average machine steel. The parts may be cast, preferably die-cast, with the steel inserts in position. The material of the parts is preferably a strong aluminum alloy.

The balls 17 are mounted, preferably immovably in sockets 28, 28 in the ends of steel screws 29, 29. The screws are shown as provided with screw driver slots 30 for adjusting them. Lock nuts or any other known or desired locking means may be employed for holding the screws in desired adjusted position though my experience has been that where close fitting screws of con-

siderable size are used, the friction is sufficient to render such locking means unnecessary, except where it is desired to prevent the user from too easily tampering with the adjustment.

The manner of assembling and adjusting the device will be evident from Figs. 4 and 5. The washers 24 are slipped over studs 19. The wire 22 is inserted through the lower transverse passage on one of the studs, 75 through the lever insert 15 and through the other stud. It is then drawn perfectly straight and clamped by washers 25, 25. The other wire 23 is then similarly threaded, washers 26 applied and clamping nuts 27 80 screwed down. The screws 29 are then rotated to force the bearing balls against the surface of the steel insert on the under side of the lever to deflect the wires and stretch them to the required high tension. The 85 screws may be rotated to advance the balls alternately until the desired position is reached. For convenience in assembling and adjusting the parts, the insert bearing surface on the stylus lever preferably has 90 two parallel shallow grooves 16, 16, formed on straight lines lengthwise of the lever and formed transversely on concave curves of much greater radius than the radius of the 95 balls, so that so far as concerns their functioning as bearing surfaces after the device is assembled, they are not different from the plane surfaces. During the alternate adjusting operation the concave cross section is useful in preventing side-slip of the lever 100 and in locating it symmetrically upon the two balls.

A desirable embodiment of my invention may be obtained by making the parts in the proportions shown in Figs. 4 and 5 and on a scale such that the balls 17, 17, will be about one-eighth inch in diameter and using No. 12 steel piano wire which is about .029 inch diameter and has a tensile strength of over 200 pounds. In the initial position shown in Fig. 4, all of the wires between the clamps will be free to stretch but only about half of it, that is one-quarter on one side of the lever and another quarter on the other side of the lever will be free for 110 deflection by adjustment of the ball bearings. In the particular adjustment shown in Fig. 5, therefore, the tension has stretched the total length of the wire between the clamps about 20%, and the free portions of 120 the wire have been deflected to an angle of about 45° to the pivotal axis. At this angle, half of the total tension on the wires will be available for downward pressure of the lever upon the balls. As the tensile strength 125 of the No. 12 wire will permit a safe tension of 50 to 100 pounds or more, the downward pressure on each ball may be 25 to 50 pounds or even more. As the contact between a polished sphere and a polished plane 130

surface is theoretically a point, it will be appreciated that these pressures reckoned as pressures per square inch are so enormous that the sphere surface must flatten 5 or the plane surface indent enough to give something more than point contact.

Of course the continued high frequency vibration to which these highly tensioned wires are subject in ordinary use will cause 10 a certain amount of permanent lengthening of the wires thereby somewhat decreasing the maximum tensions and pressures above noted, but it will be evident that the greatest possible reduction of pressure obtainable in 15 this way will not substantially alter the nature of the enormous pressure of contact of the bearing surfaces. Long continued practical use of the device shows that an absolutely non-slip engagement of the surfaces 20 is established even though the surfaces be hard polished steel well lubricated, and such engagement is maintained even though the device be kept in continuous use for long periods.

While I have given the above illustrative example of dimensions, strengths and proportions that may be employed in producing a desirable embodiment of my invention it will be evident that wide variations are possible 30 without departing from the spirit thereof.

For instance, the wires may be put under a certain amount of initial tension at the time they are drawn straight as in Fig. 4, 35 in which case the tension contemplated in Fig. 5 will be attained by screwing up the bearing screws a shorter distance than there indicated, or, by screwing up the bearing screws the same distance shown in Fig. 5, 40 a greater tension will be attained. Also screwing up the bearing screws to deflect the wires a certain distance before the clamping nuts are screwed tight, will give less tension when the bearing screws are adjusted to the position shown in Fig. 5. Obviously, also, a given distance of bearing 45 adjustment will give less tension when the clamping points are farther apart so that there is a greater length of wire to be stretched, and more tension when the clamping points are closer together.

Various sizes of wire may be employed and I have used larger piano steel wires up to .05 inch in diameter and smaller ones down to and below .01. The larger the wires and the shorter the lengths of the free portions between the fixed clamp and the point of lever engagement the greater will be the circular and transverse elasticity 55 (stiffness) of the material, capable of figuring as a factor of the resilience of the pivotal movement of the lever. With the smaller size wires, however, substantially all the pivotal resilience will be due entirely 60 to lengthwise stretching of the wires. More-

over, it is to be noted, that even in the case of the thicker wires, the geometrical relations are such that rocking the lever through the extremely small angles necessary for phonographic work, requires practically no lateral movement of the lever engaging end 70 of the wire. Hence, lateral stiffness is not an appreciable factor. By reference to Fig. 5, it will be seen that this is particularly true of the lower wire 22 which engages the 75 lever along a line only slightly beyond the line of pivotal contact of the bearing surface with the ball, and is less true of wire 23 which not only engages the lever on a line much farther beyond the bearing surface, but also has its fixed clamping points 80 on a line beyond said surface.

The modifications shown in Figs. 6, 7 and 8 will be easily understood from the foregoing. The lever shoulder shown at 31, 85 Fig. 3, is slightly exaggerated in Fig. 7 and the insert 15' is located therein with its bearing surface and wire perforations transverse to the longitudinal axis of the lever instead of parallel therewith. Co-relatively, 90 the ball bearing screws 29' and the wires 21', 22', as well as the screw studs 19', 19' are arranged in or parallel with the plane of the diaphragm instead of at right angles thereto. The ball bearing screws 29' are 95 shown as secured in the desired position of adjustment by lock screws 32, 32. Said ball bearing screws are inserted from within the cavity in the box frame and adjusted to required tension before the diaphragm is put 100 in place.

The use of clamping nuts for coupling the lever to the diaphragm is of special convenience for determining the normal or rest position of the lever with respect to the diaphragm and these nuts may be adjusted so that both diaphragm and lever are in normal rest positions without any initial tension in either direction, or they may be more or less tensioned either toward each other or 110 away from each other, as desired.

In Figs. 9 and 10 a modified form of stylus lever is shown having a passage for a single wire, formed by registering grooves in adjacent faces of the steel clamping plates 115 40, 41, which are secured to the lever by screws 42, 42.

As shown in the drawings the free end of the stylus lever is provided with a needle 51 secured in the socket 52 by screw 53. 120 The latter may be screw threaded into a steel insert 54 if desired. It will be understood that where the device is to be used for recording instead of reproducing, the annular member 5 will be used for sound receiving instead of sound emitting, and a recording cutter will be substituted for the reproducing needle 51.

The various forms of stylus lever which I have shown have a common feature of con- 130

struction which I find to be peculiarly efficient and well functioning in connection with the high pressure contact of bearing surfaces characteristic of my present invention. This feature is the relatively massive block of metal located at the pivot in combination with a relatively light construction for the long arm of the lever, particularly the thin blade like construction shown in Figs. 6, 7, 9 and 10. Great strength is of course desirable at this point and more or less massiveness is therefore to be expected, but there seems to be a further acoustic advantage.

15 Apparently the mass at this point acts to some extent as a noise absorber, lessening needle noises and it seems probable that this function is better served where the mass at the pivot tapers rather abruptly into the 20 blade-like lever arm as in Figs. 6, 7 and 9 than where the transition is tapered off as in Fig. 1. My experience tends to show that this advantage would not appear if the 25 same lever arm were used in connection with the relatively light pressure pivoting characteristic of present day commercial instruments.

I claim:

1. A sound box having a diaphragm, a lever secured to the diaphragm, convex bearing surfaces on the box and co-acting surfaces on the lever adapted for rocking contact thereon, in combination with a stretched wire engaging the lever and secured to the 30 box on opposite sides thereof in a plane passing through to the line of pivotal contact of said bearing surfaces and at equal opposite angles to said line of contact, together with means for adjusting one of said 35 bearing surfaces in said plane.
2. A sound box, diaphragm and stylus lever, in combination with a pivotal mounting therefor, comprising convex bearing surfaces mounted on the box and engaging 40 the lever, and transversely stretched wires for pressing the lever into non-slip engagement with said convex surfaces, the wires, the line of contact and the center or axis of curvature of the curved bearing surfaces all 45 lying approximately in the same plane.
3. A sound box having a diaphragm, a lever secured to the diaphragm, bearings on the box and on the lever, in combination with resilient tension means stretched 50 between the sound box and the lever on opposite sides of the latter, at substantially equal opposite angles to the line of contact of said bearing surfaces, the free portions of said wire between the box and the lever being 55 stretched in substantially the same plane with each other and with the line of contact of said bearing surfaces.
4. A sound box having a diaphragm, a lever secured to the diaphragm, bearings on the box and on the lever, in combination 60

with a highly tensioned wire stretched between the sound box and the lever on opposite sides of the latter, at substantially equal opposite angles to the line of contact of said bearing surfaces, the free portions of said wire between the box and the lever being 70 stretched in substantially the same plane with each other and with the line of contact of said bearing surfaces.

5. A sound box having a diaphragm, a lever secured to the diaphragm, bearings on the box and on the lever, the box bearing having a convex curved surface, in combination with resilient tension means stretched 75 between the sound box and the lever on opposite sides of the latter, at substantially equal opposite angles to the line of contact of said bearing surfaces, the free portions of said wire between the box and the lever being 80 stretched in substantially the same plane with each other and with the line of contact of said bearing surfaces.

6. A sound box having a diaphragm, a lever secured to the diaphragm, bearings on the box and on the lever, the box bearing 85 having a convex curved surface, in combination with a highly tensioned wire stretched 90 between the sound box and the lever on opposite sides of the latter, at substantially equal opposite angles to the line of contact of said bearing surfaces, the free portions of said wire between the box and the lever being 95 stretched in substantially the same plane with each other and with the line of contact of said bearing surfaces.

7. A sound box having a diaphragm, a lever secured to the diaphragm, bearings on the box and on the lever, the box bearing comprising alined steel balls, in combination with resilient tension means stretched 100 between the sound box and the lever on opposite sides of the latter, at substantially equal opposite angles to the line of contact of said bearing surfaces, the free portions of said wire between the box and the lever being 105 stretched in substantially the same plane with each other and with the line of contact of said bearing surfaces.

8. A sound box having a diaphragm, a lever secured to the diaphragm, bearings on the box and on the lever, the box bearing comprising alined steel balls, in combination with a highly tensioned wire stretched 110 between the sound box and the lever on opposite sides of the latter, at substantially equal opposite angles to the line of contact of said bearing surfaces, the free portions of said wire between the box and the lever being 115 stretched in substantially the same plane with each other and with the line of contact of said bearing surfaces.

9. A sound box, diaphragm and stylus lever, in combination with a pivotal mounting therefor, comprising convex bearing surfaces mounted on the box and engaging the 120

lever and a transversely stretched wire for pressing the lever into non-slip engagement with said convex surfaces, said wire, line of contact and center or axis of curvature of the curved bearing surface all lying approximately in the same plane, together with means for adjusting said convex bearing surfaces to increase the tension and raise the natural frequency of the free portions of the wire above the range of frequencies noticeable in the phonograph.

10. A sound box having a diaphragm, a lever secured to the diaphragm, bearings on the box and on the lever contacting with each other on a line parallel with the diaphragm and at right angles to the lever, in combination with resilient members secured to the sound box, engaging the lever, and arranged to forcibly press the lever bearing 15 surface against the box bearing surface, and means for adjusting said box bearing substantially in opposition to such pressure to vary its amount.

11. A sound box having a diaphragm, a lever secured to the diaphragm, bearings on the box and on the lever contacting with each other on a line parallel with the diaphragm and at right angles to the lever, in combination with resilient tension members, secured to the sound box and engaging the lever, arranged to afford pressure perpendicular to the contacting bearing surfaces, and adjustable means for moving said box bearing and lever substantially in 20 position to said pressure to vary the same.

12. A phonographic sound box of the type in which the diaphragm actuating lever pivots upon relatively movable bearing surfaces on box and lever respectively, and in combination with said parts, resilient means acting by longitudinal tension to insure continuous non-slip contact of said bearing surfaces.

13. A phonographic sound box of the type in which the diaphragm actuating lever pivots upon relatively movable bearing surfaces on box and lever respectively, and in combination with said parts, resilient means acting by longitudinal tension to insure continuous non-slip contact of said bearing surfaces, said resilient means being highly tensioned but arranged to afford small resilient opposition to pivotal movements of the lever.

14. A sound box, a diaphragm, a lever secured to the diaphragm, and means for pivoting the lever on the box, in combination with steel wires stretched from the box support to the lever adjacent the pivotal axis 50 of the latter to maintain the pivotal bearing surfaces in intimate contact and means for

adjusting the bearings and the lever away from said support to stretch said wires equally to any required degree of tension.

15. A sound box having a diaphragm, a lever secured to the diaphragm, bearings on the box and on the lever contacting with each other on a line parallel with the diaphragm, in combination with resilient tension members, secured to the sound box and engaging the lever, arranged to afford a pressure perpendicular to the contacting bearing surfaces, and adjustable means for moving said box bearing and lever substantially in opposition to said pressure to increase or decrease the same.

16. A sound box having a diaphragm, a lever secured to the diaphragm, bearings on the box and on the lever contacting with each other on a line parallel with the diaphragm and at right angles to the lever, in combination with a resilient tension member, secured to the sound box and engaging the lever arranged to afford pressure on the contacting bearing surfaces; said bearings including a pair of screws arranged endwise to said pressure whereby said lever may be moved in opposition to such pressure to vary its amount.

17. A phonographic sound box of the type in which the diaphragm actuating lever pivots upon relatively movable bearing surfaces on box and lever respectively, and in combination with said parts, resilient means acting by longitudinal tension to insure continuous non-slip contact of said bearing surfaces, and means for moving the lever with respect to the box in a direction to vary the longitudinal tension of the resilient members without skewing or endwise displacement of the lever or of its pivotal axis.

18. A phonographic sound box of the type in which the diaphragm actuating lever pivots upon relatively movable surfaces on box and lever respectively, and in combination with said parts, resilient means acting by longitudinal tension to insure continuous non-slip contact of said bearing surfaces, and means for moving the bearings and the lever with respect to the box in a direction to vary the longitudinal tension of the resilient members without skewing or endwise displacement of the lever or of its pivotal axis, said resilient means being highly tensioned but arranged to afford small resilient opposition to pivotal movements of said lever.

Signed at Buffalo, in the county of Erie and State of New York, this 13th day of March, A. D. 1919.

ELWOOD GRISSINGER.
